UNITED STATES PATENT OFFICE.

HOWARD A. TINKHAM, OF NORTON, MASSACHUSETTS, ASSIGNOR TO THE
WHITE WARNER COMPANY, OF TAUNTON, MASSACHUSETTS.

LOCK-JOINT COUPLING.

SPECIFICATION forming part of Letters Patent No. 683,670, dated October 1, 1901.

Application filed April 13, 1901. Serial No. 55,718. (No model.)

To all whom it may concern:

Be it known that I, HOWARD A. TINKHAM, of Norton, in the county of Bristol and State of Massachusetts, have invented certain new and useful Improvements in Lock-Joint Couplings, of which the following is a specification.

My invention relates to a lock-joint coupling.

It is especially intended for use in connecting an auxiliary radiator to the main radiator of a furnace or stove, and for convenience of illustration I have shown in the accompanying drawings the invention so applied; but it is not limited to such application.

The invention will now be fully described, and the novel features will be particularly pointed out in the claims at the close of the specification.

In the drawings, Figure 1 is a horizontal section on line 1 1 of Fig. 2, representing the dome and auxiliary radiator and connections of a hot-air furnace, the casing and some unnecessary parts being omitted. Fig. 2 is a vertical section on line 2 2 of Fig. 1. Fig. 3 is a side elevation of the dome and outlet of the radiator. Fig. 4 is an inside elevation of the hanger or collar which goes over the dome-outlet and to which the auxiliary radiator and the diaphragm-plate are attached. Fig. 5 is a vertical section on line 5 5 of Fig. 4. Fig. 6 is a horizontal section on line 6 6 of Fig. 4 when the collar is hung in the groove 8 on the flue 2.

The dome 1 has attached thereto or preferably cast integral therewith a nose or outlet-flue 2, which forms the flue to the auxiliary radiator 3. This flue is preferably arched or otherwise non-circular, with a flat bottom 4, depressed near its end to form a rest 15 for the diaphragm-plate 5, so as to produce a flush joint. The dome is formed with a flange 6 around the bottom, which shuts down on the section 7 beneath it and which constitutes the combustion-chamber. The flue 2 is formed with a peripheral groove 8 on the sides and preferably extending around over the top near the outer end to receive the beaded part 10 of collar 9. The collar 9 is formed with a yoke 20, having an internal bead or tongue 10, which fits in the groove 8. The yoke preferably has on its upper side a forked flange

11, whose two fingers include between them the boss 12, rising from the crown of the flue 2, to give greater stability to the collar 9.

The collar 9 is formed with an outwardly radiating flange 21, having bolt or rivet holes 13 by which the radiator 3 is attached to it, the radiator being also otherwise supported at the bottom. A horizontal flange 14, projecting from said collar at the bottom of the opening, lies on the depressed portion 15 of the bottom of the flue 2 to help support the diaphragm-plate 5 and forms a flush joint with the bottom 4. The diaphragm-plate 5 is preferably bolted to the depressed portion 15, but not necessarily so. The arms 16 of the diaphragm are secured to the plate 5. The diaphragm-plate 5 extends across the radiator 3 and into the draft-collar 17. The damper 18 controls the draft, so as to produce a direct or indirect draft, as desired.

19 is the collar for the smoke-pipe.

What I claim is—

1. The herein-described coupling comprising a tubular member grooved on its outer periphery, and a collar having a yoke which is formed with a tongue on its inner periphery adapted to fit in said groove when the yoke is slipped down over said tubular member, said tubular member and yoke having on their upper side portions which engage each other and assist in preventing rotation, substantially as described.

2. In a stove or furnace, a dome having a laterally-projecting outlet-flue, said outlet-flue having a groove formed in its outer periphery, and a collar formed with a yoke having on its inner periphery a tongue which fits in said groove when the yoke is slipped down over said flue, thereby securing the collar to the flue, a radiator, and an outlet-flue therefrom, a diaphragm which extends from the bottom of the dome outlet-flue into the outlet-flue from the radiator and a damper which controls the outlet from the radiator on the upperside of said diaphragm, substantially as described.

3. In a stove or furnace, a dome having a laterally-projecting outlet-flue, said outlet-flue having a groove in its outer periphery and having a bottom with a depressed end portion, a collar formed with a yoke having

on its inner periphery a tongue which fits in said groove when the yoke is slipped down over said flue, thereby securing the collar to the flue, a radiator, an outlet-flue therefrom, 5 a diaphragm whose inner edge rests on the depressed portion of the bottom of the dome-outlet and which extends through the said radiator into the outlet-flue therefrom dividing said last-mentioned outlet-flue into two

compartments, and a damper which controls the upper compartment, substantially as described.

In testimony whereof I have affixed my signature in presence of two witnesses.

HOWARD A. TINKHAM.
